(57) **CLAIM**

The ornamental design for a furniture unit, as shown and described.

DESCRIPTION

FIG. 1 is an isometric view of an ornamental design of a first embodiment of a furniture unit showing my new design.

FIG. 2 is a front orthographic view thereof.

FIG. 3 is a rear orthographic view thereof.

FIG. 4 is a right side orthographic view thereof, the left side being a mirror image.

FIG. 5 is a top orthographic view thereof.

FIG. 6 is an isometric view of a second embodiment of a furniture unit showing my new design; and,

FIG. 7 is an isometric view of a third embodiment of a furniture unit showing my new design.

The broken lines shown in FIGS. 1-3 and 5-7 are included for the purpose of illustrating environment elements only and form no part of the claimed design.

The bottom view is omitted and forms no part of the claimed design.
